UNITED STATES PATENT OFFICE.

NILS T. SELLMAN, OF NEW YORK, N. Y., ASSIGNOR, BY MESNE ASSIGNMENTS, TO SPENCER THERMOSTAT COMPANY, OF CAMBRIDGE, MASSACHUSETTS, A CORPORATION OF MASSACHUSETTS.

SAFETY DEVICE FOR BURNERS.

Application filed November 12, 1927. Serial No. 232,875.

This invention relates to safety devices for gas burners, and more particularly to automatic devices operable upon accidental extinguishment of the burner flame to shut off the gas supply of Bunsen burners or pilot lights such as are commonly associated with water heaters, boilers, stoves and other gas heating appliances. A principal object of the invention is to provide a thermostatically controlled device which will stop the flow of gas to the burner or pilot when the flame is extinguished, yet which will not normally interfere with a free supply of gas and will not cause faulty combustion or a flame of poor quality.

Although the provision of a thermostatic control within the tube of a gas lighter having a flame spreading jet has heretofore been suggested, such a construction would not satisfy the purposes of this invention, for the interposition of flow-retarding element in the gas passage of a burner operating at low pressure results in poor combustion and a feeble or unsatisfactory flame.

In a Bunsen burner, particularly, the consequent resistance to the free flow of the gas and air mixture would cause a yellow flame instead of the desired and characteristic blue flame of this type of burner. Another undesirable result of such a disposition of the thermostat is that a flame after a flashback would hold the thermostatic device at high temperature so that the gas supply would not be shut off. Furthermore, such a burner can not be cleaned successfully without detaching the thermostatic control or disturbing its adjustment.

A particular feature of the present invention accordingly resides in the provision of a thermostat associated with the exterior of the burner tube, and operated by the changes in temperature of the tube rather than by the temperature of the flame. This feature is illustrated in the accompanying drawings showing recommended embodiments of the invention as applied to a pilot burner adapted for use in gas refrigeration systems, or for similar purposes.

In the drawings:

Fig. 1 is an elevation of a burner equipped with the improved safety device;

Fig. 2 is a section on the line 2—2 of Fig. 1, with portions of the apparatus in side elevation;

Fig. 3 is a plan view of the structure illustrated in Fig. 2;

Figs. 4 and 5 are views similar to Figs. 1 and 2 showing a modified construction of safety device; and

Fig. 6 is a plan view of a metal blank suitable for the formation of a heat conducting element included in the modified structure.

The burner may be of any suitable construction, preferably of the Bunsen type as shown, and comprises gas inlet 4 connected to a supply pipe 5 and terminating at an orifice 6, a mixing chamber 7 having air ports 8 and an outer rotatable air adjusting sleeve 9, and a burner tube 10. A needle valve 11 may be provided for the orifice 6 and a cap 12 may be threaded upon an annular shoulder of the inlet pipe over the screw head of the needle valve to obviate the possibility of gas leakage.

As shown in Fig. 2 the inlet pipe 4 has a shoulder 13 spaced a short distance laterally from the top to the burner tube 10, and within the shoulder is formed an aperture 14 about which is a valve seat with which a valve 15 cooperates to control the passage of gas into the inlet. Between the shoulder 13 and the tube 10 is mounted a casing consisting of a cupped member 16, having a nipple threaded into the inlet pipe, and a second hemispherical member 17 having a peripheral flange crimped over the outer edge of the member 16. The crown of the member 17 is cut away at 18 to receive a portion of the burner tube 10 within the casing. If desired a spring clip 19 may be provided to hold the burner tightly within the casing recess, but ordinarily the dimensions of the elements will be such that the casing is supported close to the tube without additional binding means. A thermostatic disk 20 is mounted within the casing with its periphery received between the edge portions of members 16 and 17 and is connected by a stem 21 to the valve 15. In order that the disk 20 will not be so tightly gripped between the members 16 and 17 as to prevent its efficient operation, a spacer ring 21, which should be slightly (e. g. .005 inch) thicker than the disk, is preferably provided between said members. The inner diameter of the ring 21 may be slightly greater than the diameter of the disk 20, as indicated in the drawing, to prevent binding.

The disk 20 is preferably bi-metallic, being formed of two component disks welded together, the materials such as iron and brass of the respective disks having different coefficients of expansion. The disk 20 is normally cupped (as by swaging) in such direction that the component part having the higher coefficient of expansion is on the concave side. Consequently upon raising the temperature of the disk the unequal expansion of the materials forming the disk will cause a tendency to flatten the cupped surface until at a predetermined temperature a sudden curving in the opposite direction occurs, which reversal of shape will be maintained until the temperature has been substantially lowered. Thereafter upon reaching a substantially lower temperature, the disk will suddenly return to its initial shape. The materials and thickness of the component parts and the degree of curvature are so chosen that the disk will snap in one direction when heated to the desired temperature (e. g. 120° F.) and will snap back at a lower temperature (e. g. 100° F.). Suitable materials are sheet brass and nickel steel having a thickness of .005 and .005 inches respectively and suitable cupping for a disk $\frac{3}{4}$ inch in diameter is .02 inches. It will be understood however that the present invention is not limited to any particular combination of materials having different thermal coefficients of expansion but is intended to embrace in its scope any combination of materials having dissimilar thermal coefficients of expansion sufficient to cause the reversal of curvature. Furthermore, the two materials comprising the composite thermostatic disk may be secured together in any desired manner by riveting, soldering, brazing, or otherwise although it is preferred to unite the materials comprising the disk by welding or similar means to secure a substantially indivisible sheet. When the gas burner is lighted as shown in Fig. 2, the heat of the flame is transmitted to the wall of the burner tube 10 and thence into the casing and to the thermostatic disk 20 which, as shown, assumes a curve away from the burner tube 10 and thus holds the valve 15 off seat, allowing gas to flow through the inlet pipe 4. As soon as the flame is extinguished either intentionally or accidentally the burner tube 10 will be cooled substantially to room temperature and the consequent reaction upon the thermostatic disk 20 will cause the same to snap abruptly to the left of Fig. 2 closing the valve 15 and thereby shutting off the gas supply. When it is desired to relight the burner, the heat from the flame of a match held beneath the casing will change the shape of the disk to open the valve. The change of shape in the disk is decidedly abrupt whether in one direction or the other,

so that the valve is seated or unseated according to the temperature of the disk 20 which is constructed in such a manner that changes in shape occur with considerable force, so that positive closing and opening of the gas passage is insured. Owing to the inherent resiliency and rugged construction of the disk, it will operate indefinitely in a reliable and efficient manner.

In the modified construction illustrated in Figs. 4 to 6, the casing for the thermostatic control comprises a cupped member 22 fastened to the inlet pipe and having a peripheral flange 23, and a solid dished member 24 fitting within said flange with its outer surface spaced from the burner tube 25. A spacer ring 26 fits between the peripheral edge of the member 24 and the inner surface of member 22 and a thermostatic disk 27 is mounted in the casing with the spacer ring in substantially the same manner as in Fig. 2. Disposed between the margin of the disk 24 and the peripheral lip of the clamping flange 23, is a ring 28 of metal having high heat conductivity, which is provided with a conductor strip 29 leading above the burner tube and preferably having a winged tab 30 disposed around the flame of the burner. The ring 28 and its conductor strip may conveniently be formed from a metal blank stamped out as indicated in Fig. 6. The strip 29 and its tab may readily be bent into the form shown in Figs. 4 and 5 before the ring is affixed to the casing. In this type of structure the heat of the burner flame is transmitted to the casing and to the thermostatic disk 27 by the conductor strip 29; otherwise, the operation of the modified device is the same as above described, the construction of the inlet pipe, control valve and burner being substantially the same as in Figs. 1 to 3.

The combination of a thermostatic safety device constructed substantially as above described with a gas burner ensures an abrupt and positive closing of the gas inlet upon the extinguishment of the flame, and the positioning of the thermostat exterior of the burner tube not only affords an uninterrupted passage through the tube, and allows the burner to be cleaned or adjusted as freely as an ordinary burner, but also permits the thermostat to be enclosed within a casing which protects it from injury from flame, soot or other causes.

I claim:

1. In combination with a Bunsen burner having a burner tube and a supply pipe having a shoulder spaced a short distance from the outer wall of said tube adjacent its mouth, a valve in said shoulder adapted to shut off the gas supply when seated, a casing supported on said shoulder between the supply pipe and the burner tube, said casing having an opening the edge of which

- contacts with said outer wall permitting abruptly to seat the valve when the flame is extinguished. 25
- 5 contacts with said outer wall permitting the transfer of heat from the tube into the casing, and a thermostatic device within said casing and connected to said valve, said casing and arranged to hold the valve constructed and arranged to hold the valve open when the burner is lighted and abruptly to seat the valve when the flame is extinguished.
2. In combination with a Bunsen burner 10 having a burner tube and a supply pipe having a shoulder spaced a short distance from the outer wall of said tube adjacent its mouth, a valve in said shoulder adapted to shut off the gas supply when seated, a 15 casing supported on said shoulder between the supply pipe and the burner pipe, said casing having an opening the edge of which contacts with said outer wall permitting the transfer of heat from the tube into the casing, and a bimetallic disk within said casing and connected to said valve, constructed and arranged to hold the valve open when the burner is lighted and 20 abruptly to seat the valve when the flame is extinguished, said disk being mounted within said casing at its periphery.
3. In combination with a Bunsen burner having a burner tube and a supply pipe having a shoulder spaced a short distance from the outer wall of said tube adjacent its mouth, a valve in said shoulder adapted to shut off the gas supply when seated, a 25 casing supported on said shoulder between the supply pipe and the burner tube, said casing having an opening the edge of which contacts with said outer wall permitting the transfer of heat from the tube into the casing, a bimetallic disk within said casing and connected to said valve, constructed and arranged to hold the valve open when the burner is lighted and abruptly to seat the 30 valve when the flame is extinguished, said disk being mounted within said casing at its periphery.

Signed by me at New York city, N. Y., this twenty-seventh day of October, 1927.

NILS T. SELLMAN.
